UNITED STATES PATENT OFFICE.

HARRY H. SCHROYER, OF CHICAGO, ILLINOIS, ASSIGNOR TO THE ACME SUPPLY COMPANY, A CORPORATION OF ILLINOIS.

METALLIC CAR-ROOF.

1,128,373.

Specification of Letters Patent. Patented Feb. 16, 1915.

Application filed June 15, 1911. Serial No. 633,297.

To all whom it may concern:

Be it known that I, HARRY H. SCHROYER, a citizen of the United States, and a resident of the city of Chicago, in the county of Cook and State of Illinois, have invented certain new and useful Improvements in Metallic Car-Roofs; and I do hereby declare that the following is a full, clear, and exact description of the same, reference being had 10 to the accompanying drawings, and to the letters of reference marked thereon, which form a part of this specification.

Cars roofs have sometimes been constructed of metallic plates or sheets rigidly secured at the ridge and at the top of the sides or plates by sheets or plates that are seamed or otherwise rigidly joined along the meeting edges, thus affording a construction, which, with the racking or twisting of the 20 car, constantly taking place when the car is in motion, tend to constantly buckle and twist the sheets or plates forming the metallic roof, soon loosening the same and frequently causing the same to break along the 25 lines of most frequent stress, thus causing leaks. Frequently the roof of the car is first covered with boards, and then sheathed with any suitable sheet metal, as, for instance, "galvanized iron or tin and in such 30 roofs, the constant vibration due to the movement of the car soon causes the nails to pull from the wood, permitting the displacement of the sheet or breaking or tearing of the sheet due to the buckling of the 35 sheet as before described.

The object of this invention is to afford a roof construction in which individual plates or sheets affording the roof covering are engaged in place by means of metallic retaining and deflecting strips which engage over the roof cleats and bear on the edges of the sheet, and serve to lock the same in place without of necessity affording a seam therewith.

It is also an object of the invention to afford a construction in which specially shaped panels of sheet metal are arranged and secured to cover the roof in a manner to permit the greatest possible amplitude of 50 movement or adjustment during the normal movement of the car, and to obviate entirely any buckling or bearing tendency heretofore always present in such constructions.

It is also an object of the invention to afford an exceedingly cheap, simple and dura-

ble roof construction adapted for use either on cars or elsewhere.

The invention consists in the matters hereinafter described and more fully pointed out and defined in the appended claims. co

In the drawings: Figure 1 is a fragmentary top plan view of a car, the roof of which embodies my invention. Fig. 2 is an enlarged section taken on line 2--2 of Fig. 1. Fig. 3 is an enlarged detail section on line 3--3 of Fig. 1. Fig. 4 is a slightly modified construction of a joint afforded between the top and side sheets or covering. Fig. 5 is a section on line 5--5 of Fig. 1. Fig. 6 is a fragmentary top plan view of one of the 70 individual sheet metal roof panels. Fig. 7 is an enlarged top plan view of the side strip or retaining plate.

As shown in the drawings: A, indicates the roof boards or decking of the top of the 75 car which inclines laterally on each side from the center of the car top and may be constructed of wood or any other suitable material.

A', indicates the side wall of the car, 80 which extends upwardly to, and is overlapped by the roof boards A, as shown in Figs. 3 and 4. Said side walls or boards are rigidly secured at their upper ends to a plate a, on which the lower ends of the top 85 boards also are secured, and rigidly secured around the top of the car and covering the joint afforded between the top boards A, and side boards A', is a cleat or rib A², which may be of any desired thickness and co the top of which is beveled downwardly to correspond with the pitch of the roof.

Secured along the ridge of the roof and covering the joint between the oppositely inclined halves of the top is a cleat or ridge 95 plank B, of any suitable width and secured through the roof boards and into the ridge pole B', as usual or in any suitable manner. Secured at equal distances apart and at right angles with the ridge plank are ribs b, 100 spaced equal distances apart for the entire length of the car roof, the distance apart being dependent upon the width of the sheet metal panels C, which are fitted between the same. Said panels, as shown in Figs. 1, 2, 5, and 6, are shaped or pressed to afford at their sides and upper end an upwardly and inwardly curled edge, c, the margin of which is directed slightly downwardly, said edge being raised sufficiently to afford across 105 110

the upper end and down each side a concave water channel. As shown, the water channel so formed is continuous around the corners afforded by the upper end and sides 5 of the sheet. The width of said metal panels is slightly less than the distance between the separating ribs for the panels, and as shown in Fig. 3, the lower end of each panel is folded transversely and inwardly, and the margin thereof is then bent 10 outwardly and downwardly for the entire width of the sheet, and engaged along the cleat A^2 , for the entire length of the car is a metallic strip or plate D, at its upper end 15 flanged upwardly and over the cleat A^2 , as shown in Fig. 3, and as shown cut to afford a convex edge or margin, as shown in Fig. 7, adapted to engage in the lower fold at the lower or outer end of the roof panel sheet, 20 as shown in Fig. 3, the margin c' , of said roof panel extending beneath the flange d.

A metallic sheet or plate D', of a gage to afford considerable rigidity is bent to afford a central longitudinal flat face to engage on, 25 and fit over the ribs b, and the downwardly inclined margins d', thereof extend close to the upper face of the roof panel sheet C, as shown in Fig. 5, and fitted over said plate D', is a covering sheet d², which is shaped 30 to fit on said plate D', and the edges of which are rolled under the margins of said plate and bear lightly upon the upper face of the metallic roof panel just beyond the downwardly curved margin e, thereof. Extending longitudinally the ridge plank B, and fitted thereto as before described with reference to the reinforcing plate D', on the ribs is a similar metallic plate E, over which is fitted a sheet or plate of metal e, similar 35 to the covering strip d², before described and the edges of which are turned under the edges of the reinforcing strip E, as shown in Fig. 2, and bear slightly on the upper faces of the metallic roof panel. Said 40 covering strip e, also covers the upper ends of the covering strips d², for the ribs, as shown in Fig. 1.

The convexly curved inner edge d, of the side plates or strips D, are afforded a short 45 central bearing in the fold c', at the lower edge of the metallic roof panel and secured against the ridge plank intermediate between the ribs is a cleat e², against which the upper end of the metallic roof panel 50 bears at its center. The sides of the roof panels, as shown in Fig. 1, are wholly out of contact both with the ridge plank and the lateral ribs b', and said metallic roof panels are held in place solely by means of 55 the engagement at the lower end of the sheet with the inwardly turned edge d, of the side plate or strip, and also by the bearing on the inner face of said sheets of the infolded edges of the covering strips d² and e². 60

65 The outer sides or edges of each of the

sheets C', affording the end roof panel may be folded or seamed, as shown in Fig. 3, with reference to the lower end of the roof panel C, or if preferred, may be otherwise engaged in place. If preferred, a single 70 bend or fold c⁵, may be afforded at the lower edge of each roof panel and the side strips may be folded inwardly d⁴ and then outwardly as at l⁶, as shown in Fig. 4, affording a recess between the folds to receive 75 the inwardly directed edge c⁵, of the roof sheet or panel. In this construction, of course, either edge of the roof sheet or the outer folded edge of the side strip may be convexly curved, in either case affording a 80 short bearing on the complementary sheet or member.

The operation is as follows: The metallic covering of the roof is very quickly secured in place, inasmuch as the metallic roof panels are simply distributed in place between the ribs b, the side strips D, are next secured in place, and the upper flanged edge thereof hooked into the fold or flange in the lower margin of the roof panel, thus holding 85 the roof panel from sliding outwardly. The rib plates D', are next secured in place on the ribs with the inturned edges of the covering strip d², thereon bending inwardly 90 sufficiently to afford a slight bearing on the upper face of the roof panel. The plate E, and covering strip e, are next secured in place with the downturned edges or flanges thereof extending sufficiently low for the rounded edge of the covering strip e, to bear 95 on the end of said sheet metal roof panel, as shown in Fig. 2. The engagement of said plates covering the strips together with the side strip and flange d, serve to positively 100 secure each of said sheet metal roof panels 105 in place while permitting considerable amplitude of movement under the motion of the train. This will be evident from the fact that the sheet rests flat upon the roof boards and has no confining or riveting 110 bearing on either the ridge plank or ribs except upon the chuck or block e², secured to the ridge plank and against which the head of the roof panel bears centrally. This, together with the bearing afforded by the 115 rounded inturned edge d, of the side strip, insures the greatest of freedom of adjustment and movement of the roof panel to conform to the twisting and straining or vibration, and obviously from the construction described, sufficient stress can never be applied to any of the metallic portions of the roof under the normal operation of the car to break, damage or otherwise injure the 120 same. Water can never penetrate the roof even during high winds inasmuch as the rain or snow falling on the roof and into one of said panels is quickly drained therefrom by the pitch of the roof and if any portion thereof (by the action of the wind 125

or otherwise) should be driven upwardly against the edge of the covering strip either for the ribs or for the ridge plank, the covering strips serve to deflect the same.

- 5 Should any water under any circumstances find its way past the downturned edge of the covering strips, such amount will be stopped in the concave and upwardly turned and rolled edge of the sheet, which serves
  - 10 to direct the flow laterally to the side channels in said sheet, thus permitting the water to drain from the roof.
- Obviously, repairs can be effected with the greatest facility when necessary and at
- 15 any time any section of the roof may be removed and replaced by a new section by simply raising the plates D' and E, and the corresponding cover strips therewith to permit the defective panel to be slid out from
  - 20 beneath the same.

Of course, I am well aware that details of construction may be varied and that a roof embodying my invention may be used for numerous purposes other than car roofs.

- 25 I therefore do not purpose limiting this

application for patent otherwise than necessitated by the prior art.

I claim as my invention:

In a device of the class described retaining members secured to the ridge and cross members comprising a relatively stiff metal strip, the central portion thereof substantially flat, the opposite edges thereof bent in two different planes, a thinner strip bent closely around said stiff strip and beaded 30 completely over the edges of the same affording a smooth contact surface, and a plurality of pans, the flanged edges thereof engaged beneath said bent plane edges of the metal strip and said contact surface bearing 35 down on the bottom of the pans to hold them in the plane of the car roof.

In testimony whereof I have hereunto subscribed my name in the presence of two subscribing witnesses.

HARRY H. SCHROYER.
